UNITED STATES PATENT OFFICE.

ELIZABETH STREBECK, OF ST. LOUIS, MISSOURI.

DESIGN FOR A FRUIT-HOLDER.

SPECIFICATION forming part of Design No. 26,633, dated February 16, 1897.

Application filed December 23, 1896. Serial No. 616,815. Term of patent 7 years.

To all whom it may concern:

Be it known that I, ELIZABETH STREBECK, of the city of St. Louis, and State of Missouri, have invented a new and original Design for 5 Individual Fruit-Holders, of which the following is a full, clear, and exact description, reference being had to the accompanying drawings, forming a part hereof.

In the drawings, Figure 1 is an edge elevation of an individual fruit-holder, showing 10 my design and taken looking in the direction indicated by the arrow 1 in Fig. 2. Fig. 2 is a sectional view taken approximately on the line 2 2 of Fig. 1 and looking in the direction 15 indicated by the arrow.

The leading feature of my design consists 20 of a concavo-convex disk having a handle projecting from its convex side and a point 25 projecting from its concave side, said handle and point being substantially in alinement.

The concavo-convex disk 3 has the bead 4 extending around its edge, and the handle 5 projects from the convex side of said disk 25 and at approximately its center. The handle 5 is substantially rectangular in cross-section, being several times wider than it is

thick and has the lugs 6 and 7 formed upon its edges and near to the convex side of the disk 3. The opposite end 8 of the handle 5 30 from the disk 3 is rounded and is somewhat wider than the body portion of said handle. The point 9 projects from the concave side of the disk 3 and substantially in alinement with the handle 5, and said point is substantially 35 the same thickness as said handle. The edges 10 and 11 of said point come together at the opposite end of said point from the disk, thus forming an acute angle. The edge 10 is substantially straight near the disk 3, while the 40 edge 11 has the curved portion 12, forming the lug 13 at the junction of the handle 5 with said point 9, which lug rests against the inner face of the disk 3.

I claim—

The design for an individual fruit-holder, as herein shown and described.

In testimony whereof I affix my signature in presence of two witnesses.

ELIZABETH STREBECK.

Witnesses:

EDWARD E. LONGAN,
MAUD GRIFFIN.
